UNITED STATES PATENT OFFICE.

AUGUSTUS H. BRINKMANN, OF BALTIMORE, MARYLAND.

BUSTLE.

SPECIFICATION forming part of Letters Patent No. 358,726, dated March 1, 1887.

Application filed October 12, 1885. Serial No. 179,702. (No model.)

To all whom it may concern:

Be it known that I, AUGUSTUS HERMAN BRINKMANN, a citizen of the United States, residing at Baltimore city, in the State of Maryland, have invented new and useful Improvements in Bustles, of which the following is a specification.

I have improved the bustle having tubular-wire springs connected by bows to end braces and supported by independent flexible transverse tapes, and while I do not claim, broadly, such a construction, I have combined with such construction of independently-supported tubular-wire springs and rigid end braces, *d*, back-lacing supports *j*, attached to and forming extensions of pockets for said end vertical braces, whereby to allow of the adjustment of the lower spring-coil toward and from the body of the wearer, to give more or less projection to the skirts, for by lacing up the back-supports the lower horizontal tubular coil will be projected out from the body by the action of the vertical end braces upon the hips, so as to draw the ends of the lower tubular coil inward upon the body, and by letting out the lacing the back-supports *j* will allow the lower ends of the vertical end braces to stand out sufficiently to cause the lower coil to set nearer the back of the wearer, and therefore have less projection to give the desired set to the skirts.

Referring to the accompanying drawings, Figure 1 represents in perspective my bustle; Fig. 2, a cross-section of the same. Fig. 3 shows the waistband and the back adjustable lacing-supports for varying the size and elevation of the bustle to suit the set and length of dresses of different material, and particularly light and heavy dresses. Fig. 4 shows one of the tapes forming a pocket for connecting the ends of the several rolls of different lengths, arranged in horizontal relation one above and independent of the other; Fig. 5, a detail showing the manner of fastening the spiral coils to form the spirally-wound roll; and Fig. 6 a part of one of the coiled rolls with end-strip braces, *d*.

The bustle is made of two or more coils of spirally-wound wire, being wound so as to make the coil taper from middle to its ends. The wire so wound has its ends fastened at the end coils by metal clasps *a*, and its coils are fastened at one side to two parallel wire strips, *b*, by metal clasps *a*, the said strips *b*

extending beyond the ends of the coils and 55 clinched over end-strip pieces, *d*, as shown in Fig. 6. Each coil so made is connected to tapes *e*, which form end pockets to cover the end strips, *d*, and serve to attach the coils to the waistband *f*, which has the fastening- 60 buckle. The springs are connected by the end-strip pieces, *d*, in horizontal relation, one above the other, so that the longest one will be at the bottom and the shortest one at the top to give a step-like graceful form to skirts resting over upon the bustle. A loose middle tape, *g*, on the inner sides of the rolls connects the several coils together and to the waistband by clasps. The strips *b* of each coil are fastened to the end-pocket tapes by 70 clinch-buttons *i*, and the bustle so made of three or more coils is light, flexible, and durable. Lacing-supports *j* of cotton are fastened by the clinch-buttons *i* within the end-pocket tapes at the inner side of the bustle, so 75 as to rest upon the skirts at the back, and lacing-cord *l* serves to adjust the bustle to the size, to suit the weight and length of dress upon the hips.

By drawing the lacing-cord together the 80 ends of the coils are brought nearer together, and the bustle is thereby caused to stand out and to be elevated, according as the ends are brought together. By letting out the lacing-cord the lower end of the end-pocket tapes, *e*, 85 stand wide apart over the hips and give a different set to the dress.

The metal end pieces, *d*, serve to brace the ends of the bustle and to keep the coils in proper relation to each other and to the waistband. 90

I claim—

The bustle herein described, consisting of two or more tubular-wire spring-coils overlying each other in independent relation, each 95 coil having one or more bows connected at their ends by braces *d*, the tape-pockets *e* for said braces, the loose transverse tapes *g*, separately connecting each tubular spring, the lacing-supports *j*, and the waistband *f*, as 100 shown and described.

In testimony whereof I have hereunto set my hand in the presence of two subscribing witnesses.

AUGUSTUS H. BRINKMANN.
